UNITED STATES PATENT OFFICE.

AUGUST STACHOFSKI, OF WHITLA, ALBERTA, CANADA.

S HOOK.

Application filed September 26, 1921. Serial No. 503,173.

To all whom it may concern:

Be it known that I, AUGUST STACHOFSKI, a subject of the King of Great Britain, a resident of the village of Whitla, in the Province of Alberta, Canada, have invented 5 certain new and useful Improvements in **S** Hooks, of which the following is the specification.

My invention relates to improvements in 10 **S** hooks and the object of the invention is to devise an **S** hook for connecting the ends of chains thereto or for other purposes in which the links or rings applied to the **S** hook will be prevented from becoming disengaged therefrom.

My invention consists of an **S** hook constructed and arranged substantially as hereinafter more particularly described and illustrated in the accompanying drawing 20 in which:

Fig. 1 represents a side elevation of an **S** hook constructed according to my invention showing a link of a chain about to be applied to one end thereof and illustrating the 25 means for preventing the displacement of the link therefrom.

Fig. 2 is a similar view to Figure 1 showing the link in position at one end of the **S** hook, and

Fig. 3 is an elevational view taken at right angles to Figures 1 and 2.

Like characters of reference indicate corresponding parts in the different views.

1 represents the **S** hook provided with the 35 hooked ends 2. 3 is a longitudinal slot in the central portion of said **S** hook. 4 and 5 are concentric discs rotatably mounted in the slot 3 on the pivot pin 6. 7 is a slot extending inwardly from the periphery of the 40 disc 4 and 8 is a similar slot extending inwardly from the disc 5. 9 is a link of a chain.

My device is used as follows:

The discs 4 and 5 are turned so that the slots 7 and 8 therein register one with the 45 other and then both discs are turned so that the end link of a chain can be inserted into said slots. The discs are now turned back until the link 9 will drop into the hook-shaped end 2 when they are further turned 50 so that the slots 7 and 8 will be out of register one with the other.

It will be seen that in the latter position the link will be prevented from becoming disengaged from the **S** hook as it will engage the periphery of the discs. Such discs are sufficiently large to enter the slots 10 in the tips of the hook portions 2.

Although I have shown a link applied to one end of the **S** hook it will be understood 60 that links can be applied to each end in the manner above described.

To remove the link from the **S** hook it is merely necessary to turn the discs 4 and 5 so that the slots 7 and 8 register and then 65 turn the discs simultaneously into such a position that the upper portion of the link can be inserted into such slots, then by turning the discs simultaneously so that the slots clear the hooked end it will be seen that the 70 link can then be removed therefrom.

What I claim as my invention is.

In an **S**-hook having a longitudinal slot in the central portion thereof, and slots in the opposed tips of the **S**-hook, a plurality 75 of independent concentrically journaled discs positioned in said longitudinal slot in the central portion of the **S**-hook, each of said discs having a slot extending inwardly from the periphery thereof, and each of 80 said discs entering a slot in the opposed tips of the **S**-hook.

AUGUST STACHOFSKI.
